UNITED STATES PATENT OFFICE.

CLAYTON D. HIMEBAUGH, OF BURR OAK, MICHIGAN, ASSIGNOR TO ADELBERT C. HIMEBAUGH, OF BURR OAK, MICHIGAN.

BOB OR COASTING SLED.

1,194,383.

Specification of Letters Patent. Patented Aug. 15, 1916.

Application filed December 27, 1915. Serial No. 68,773.

To all whom it may concern:

Be it known that I, CLAYTON D. HIMEBAUGH, a citizen of the United States, residing at Burr Oak, county of St. Joseph, and 5 State of Michigan, have invented certain new and useful Improvements in Bob or Coasting Sleds, of which the following is a specification.

This invention relates to an improved bob 10 or coasting sled.

The main objects of this invention are: First, to provide in an improved bob sled, an efficient and adjustable tension means for facilitating the steering of the same. Second, to provide in an improved bob sled, an adjustable tension means whereby the front sled will be returned to its normal position after any turning effort has been removed from the same.

20 Further objects, and objects relating to details and economies of construction and operation will definitely appear from the detailed description to follow.

I accomplish the objects of my invention 25 by the devices and means described in the following specification.

The invention is illustrated in the accompanying drawings forming a part of this specification, in which:

30 Figure I is a side elevation of my improved bob or coasting sled embodying the features of my invention. Fig. II is an inverted plan view of the said bob or coasting sled. Fig. III is an enlarged partial detail 35 horizontal section showing the operation and connection of the front sled tension means taken on line 3—3 of Figs. I, IV and V. Fig. IV is an enlarged partial detail vertical section showing the connection of 40 front sled to the spring tension means, taken on line 4—4 of Figs. II and V. Fig. V is an enlarged partial detail vertical section through the front sled king bolt, taken on line 5—5 of Figs. I, II and IV.

45 In the drawings similar reference characters refer to similar parts throughout the several views, and the sectional views are taken looking in the direction of the little arrows at the ends of the section lines.

50 Referring to the drawings, the bob sled top 1 consists of boards held together by the front bolster 2 and rear beam 3 respectively. The rear sled consists of the runners 4 which are connected to beam 3 by the 55 knees 5 fastened at their forward ends to

the top 1. The front sled consists of runners 6 fastened at the front end by steering cross arm 7, the knees 8 of which are securely connected to beam 9 of channel iron. A rave-like brace 10 connects the nose of 60 each runner to the beam 9. The beam 9 is adapted to turn and bear against the bolster 2, said bolster 2 having on its under side the metal bearing plate 11 which forms the bearing surface for the beam 9. The 65 front sled steering or king bolt 12 is adapted to pass through the bolster 2 and the beam 9 thus permitting the front sled to turn for steering. In the bolster 2 and next to plate 11 is a notch adapted to engage one of the 70 spring yoke halves 13. This yoke half has a slot 14 through which passes the bolt 12. On the under side of the cross piece 9 is also disposed the lower yoke half 15 with a similar slot in it through which the bolt 12 75 passes. In front of beam 9 and pivoted on pin 17 between the forward ends of the yoke halves 13 and 15 is the rock bar 16. Connecting the rear ends of the two yoke halves is the tension spring 18. Spring 18 is 80 hooked at its rear end to the eye bolt 19. Eye bolt 19 passes through a guard piece 20 and has at its rear end the wing nut 21. Variable tension is thus put on the spring when wing nut is turned. The front end of 85 the guard piece 20 is fastened beneath the lower yoke half 15 by the king bolt nut 12', as shown, the rear end of said guard 20 being fastened to the sled top 1. Around king bolt 12 and within the channeled portion of 90 beam 9 is the compression spring 22 serving to keep the adjacent parts in a yielding relation to each other. The slot in yoke half 15 is somewhat wider than that of yoke half 13 to permit spring 21 to pass through 95 thus giving the same degree of movement to each. Therefore, when the front sled is turned, as shown in Fig. III, one end of rock bar 16 will bear against that half of the front sled beam 9 which swings forward 100 about the king pin 12. The other end of the rock bar 16 will fulcrum on bolster 2 and the resultant forward movement of pin 17 will stretch the spring 18. The slots in the yoke halves allow the necessary transverse movement of the same besides giving flexibility to the whole arrangement. Tension is, therefore, put in the spring so that when the steering arm is released, the front sled will be brought back to its normal pos- 105 110

tion. Also when the front sled is turned to make a curve, the spring causes a steady pull on the steering arm which is advantageous for careful steering. I have thus 5 produced a tension means and centering means by the action of a single spring.

I have illustrated and described my improved sled in detail in the form in which I have embodied the same for the market. I 10 have not attempted to illustrate or describe possible modifications and variations in structural details, which I contemplate, as I believe the disclosure made will enable those skilled in the art to which my invention relates, to embody my improvements as conditions may require. I desire, however, to be understood as claiming my improvements specifically in the form illustrated, as well as broadly, as appears in 15 the appended claims.

Having thus described my invention, what I claim as new and desire to secure by Letters Patent is:

1. In a bob sled, the combination of the 25 top, a rear bob secured thereto, a bolster at the front, a front bob, a king bolt, a brace bar secured to the sled top toward its rear and to the king bolt at its forward end, a slotted yoke made up of members above and 30 below the beam of said front bob, a pivoted cross rock bar pivoted between the yoke members and adapted to rest yieldingly against the forward side of the said bolster and beam, a spring secured at its forward 35 end to said yoke, and an adjustable bolt for securing the rear end of said spring to said brace bar, coacting substantially as described for the purpose specified.

2. In a bob sled, the combination of the 40 top, a rear bob secured thereto, a bolster at the front, a front bob, a king bolt, a brace bar secured to the sled top toward its rear and to the king bolt at its forward end, a slotted yoke, a pivoted cross rock bar pivoted 45 to the yoke and adapted to rest yieldingly against the forward side of the said bolster and beam, a spring secured at its forward end to said yoke, and an adjustable bolt for securing the rear end of said spring to said

brace bar, coacting substantially as de- 50 scribed for the purpose specified.

3. In a bob sled, the combination of the top, a rear bob secured thereto, a bolster at the front, a front bob, a king bolt, a brace bar secured to the sled top toward its rear 55 and to the long bolt at its forward end, a slotted yoke made up of members above and below the beam of said front bob, a pivoted cross rock bar pivoted between the yoke members and adapted to rest yieldingly 60 against the forward side of the said bolster and beam, a spring secured at its forward end to said yoke, and means for connecting the rear end of said spring to said brace bar, coacting substantially as described for the 65 purpose specified.

4. In a bob sled, the combination of the top, a rear bob secured thereto, a bolster at the front, a front bob, a king bolt, a slotted 70 yoke made up of members above and below the beam of said front bob, a pivoted cross rock bar pivoted between the yoke members and adapted to rest yieldingly against the forward side of the said bolster and beam, a spring secured at its forward end to said 75 yoke, and an adjustable bolt for securing the rear end of said spring to said top, co-acting substantially as described for the purpose specified.

5. In a bob sled, the combination of a 80 slotted yoke embracing the king bolt, a pressure bar disposed to brace against the forward side of the bolster and knee of the forward bob, an adjustable spring for putting tension on said yoke, as specified. 85

6. In a bob sled, the combination of a slotted yoke embracing the king bolt, a pressure bar disposed to brace against the forward side of the bolster and knee of the forward bob, a spring for putting tension 90 on said yoke as specified.

In witness whereof, I have hereunto set my hand and seal in the presence of two witnesses.

CLAYTON D. HIMEBAUGH. [I. S.]
